E. W. Marshall

UNITED STATES PATENT OFFICE.

JOSEPH KENNEDY, OF NEW YORK, N. Y., ASSIGNOR TO J. EDWARD OGDEN, OF MOUNTAINVILLE, NEW YORK.

EXPANSION-BOLT.

1,293,465.

Specification of Letters Patent. Patented Feb. 4, 1919.

Application filed May 22, 1917. Serial No. 170,118.

To all whom it may concern:

Be it known that I, JOSEPH KENNEDY, a citizen of the United States of America, and a resident of New York, county and State of New York, have invented certain new and useful Improvements in Expansion-Bolts, of which the following is a specification, reference being had to the accompanying drawings, forming a part thereof.

My invention relates to new and useful improvements in expansion bolts and its object is to improve upon structures of this kind and to provide a simple device by means of which a more secure anchorage for a bolt in a wall or other structure with which the threads of a bolt cannot engage directly, than have been obtainable by the use of such devices as heretofore have been available. More specifically the invention relates to that type of anchorage which comprises an expansible shell with a tapered member movable longitudinally therein by means of which the desired expansion is obtained and its object is to so construct the tapered member that the pressure produced by the movement thereof to expand the shell is utilized to grip and hold the bolt itself.

In order that my invention may be thoroughly understood I will now proceed to describe the same in the following specification and then point out the novel features thereof in appended claims.

Referring to the drawings:

Figure 1 is an elevation of a device made according to and embodying my invention, showing the position of a bolt therein before expansion.

Fig. 2 is a longitudinal sectional plan view of the same parts with the bolt shown in elevation.

Fig. 3 is a sectional end elevation on an enlarged scale, of the same device, the section being taken on the line 3-3 of Fig. 2.

Fig. 4 is a similar sectional end elevation, the section being taken on the line 4-4 of Fig. 1.

Fig. 5 is a sectional side elevation of the collar shown in Figs. 1 and 2.

Fig. 6 is an end elevation of the same collar.

Like characters of reference designate corresponding parts in all the figures.

10 and 11 designate like members which together form a hollow cylindrical shell. Each of these members is provided with lugs

12 which register with and are arranged to be bent into depressions 13 in the other member when the device is assembled to hold the members and the parts therein together. These members are constructed to form between them a cylindrical bore 16 which near the ends is tapered to flare outwardly. The adjacent edges of the members are cut away opposite these tapered portions so that when assembled they form between them diametrically opposed slots 14 and 15, the edges of which are preferably undercut as shown in Fig. 3.

Fitted in one of these tapered portions is a collar 20 and in the other an internally threaded nut 30. The collar 20 extends beyond the end of the shell formed by the members 10 and 11. It has a central bore of a diameter large enough to clear the shank of a bolt 40. It also has a pair of oppositely extending lugs 22 which project into the slots 15 but not beyond the periphery of the shell. These lugs are longitudinally shorter than the slots and prevent the collar from moving out of the shell but the longer length of the slots provides for a movement of the collar into the shell. Their sides are preferably undercut as shown in Fig. 6.

The body of the collar is slotted longitudinally from the inner end as shown at 23 for a material part of its length and the outer surface of the part of collar which extends outwardly beyond the ends of the slots is provided with less taper than that of the tapered part.

The nut 30 is similarly constructed except that instead of a clearance hole for the bolt it is internally threaded as at 31 to receive the threads 42 of the bolt. Its lugs which extend into the slots 14 are designated by 32 and its slots by 33.

In operation, a hole is drilled in a wall or other object of concrete, brick or other material of such a character that the threads of a bolt cannot make satisfactory engagement therewith. The hole is made deep enough to receive the bolt anchor and of a diameter to form a clearance fit therefor. Now when a bolt 40 is inserted through the collar 20 and into the nut 30, its length is such that either the inside of its head 41 will engage the outer end of the collar, or, as is more often the case, an object to be held by the bolt will come between and be in contact with the inside of the head of the bolt and

the outer end of the collar. In either case, tightening the bolt will draw the collar 20 and the nut 30 toward each other. During such an operation the lugs 32 will prevent 5 rotation of the nut relative to the shell.

The inner movement of either the collar or of the nut or of both, will force the shell members 10 and 11 apart and into binding engagement with the walls of the hole in 10 which the device has been inserted. This is due to the pressure exerted upon the shell members by reason of their tapered shape. This pressure reacts upon the collar and upon the nut, which on account of the slots 15 therein, will be forced inwardly against the shank of the bolts and upon the threads 42 thereof.

Thus the collar will firmly grip the bolt and hold it solidly in position without any 20 opportunity for lateral vibration which would in time loosen an originally tight anchorage.

Forcing the nut onto the threads of the bolt has a similar effect of firmly gripping 25 the bolt and an added effect of locking the threads so that the bolt will not work out of the nut.

It may be seen that with this device a most effective anchorage may be obtained. 30 It is of course within the scope of my invention to use either a collapsible collar or a collapsible nut. I do not intend to limit myself to the use of both. The invention may be embodied in other structures than 35 that shown and described, and I intend no limitations other than those imposed by the appended claims.

What I claim is:

1. A transversely expandable shell having 40 a longitudinal bore with flaring portions near the ends thereof, an externally tapered expansion member in the flaring part of the bore near one end of the shell, and an externally tapered nut in the flaring part of 45 the bore near the other end of the shell, said nut being internally threaded to receive the threads of a bolt, said expansion member and nut being constructed and arranged

to produce an expanding pressure upon said shell by being oppositely moved longitudinally therein and to be contracted against the bolt by said pressure.

2. A transversely expandable shell having a longitudinal bore flaring outwardly near the ends thereof, an externally tapered collar in the flaring part of the bore near one end of the shell and extending beyond the end of the shell and having a clearance hole for a bolt, and an externally tapered nut in the flaring part of the bore near the other end of the shell, said nut being threaded to receive the threads of a bolt, said collar and nut being constructed with longitudinal slots and arranged to be moved toward each other within the shell by a bolt to thereby produce an expanding pressure upon said shell and to be contracted against the bolt by said pressure.

3. A plurality of members together forming a longitudinally divided hollow shell having outwardly flaring openings at the ends thereof, said shell being constructed with slots in its walls opposite said flaring portions, an externally tapered collar in the flaring part of the shell at one end thereof extending beyond the end of the shell and having a clearance hole for a bolt, a lug projecting from the collar into one of the slots in the wall of the shell, and an externally tapered nut in the flaring part of the shell at the other end thereof, said nut being internally threaded to receive the threads of a bolt, a lug projecting from said nut into another of the slots in the wall of the shell, said collar and nut being provided with longitudinal slots and arranged to be moved longitudinally within the shell toward each other to thereby produce an expanding pressure upon said shell and to be contracted against the bolt by said pressure.

In witness whereof, I have hereunto set my hand this 14 day of May, 1917.

JOSEPH KENNEDY.
